Primary Examiner — David G Muller(74) *Attorney, Agent, or Firm* — Reinhart Boerner Van Deuren P.C.(57) **CLAIM**

I claim the ornamental design for the bench clamp mount and alignment feature, as shown and described.

DESCRIPTION

FIG. 1 is a perspective view of an embodiment of the bench clamp mount and alignment feature:

FIG. 2 is a top view thereof;

FIG. 3 is a bottom view thereof;

FIG. 4 is a front view thereof;

FIG. 5 is a rear view thereof;

FIG. 6 is a side view thereof;

FIG. 7 is a side view thereof showing the side opposite that shown in FIG. 6; and,

FIG. 8 is an exploded perspective view thereof.

The broken lines show portions of the design that form no part of the claimed design. The dash-dot broken lines are boundary lines identifying portions of the design that form no part of the claimed design.
